UNITED STATES PATENT OFFICE.

WILLIAM T. DODD, OF BROOKLYN, NEW YORK, ASSIGNOR TO NATIONAL ROLLER GIN COMPANY, OF PHOENIX, ARIZONA, A CORPORATION OF ARIZONA.

COTTON-GIN.

1,226,317.

Specification of Letters Patent.

Patented May 15, 1917.

Application filed December 2, 1912, Serial No. 734,509. Renewed October 20, 1916. Serial No. 126,799.

To all whom it may concern:

Be it known that I, WILLIAM T. DODD, a citizen of the United States, and a resident of the city of New York, borough of Brooklyn, in the county of Kings and State of New York, have invented a new and Improved Cotton-Gin, of which the following is a full, clear, and exact description.

My invention has for its object to provide 10 a cotton gin, with novel parts disposed to obtain a more thorough cleaning of the cotton than is possible with cotton gins now in use, and to treat and straighten the cotton fibers. Other objects of the invention 15 are to construct the ginning rolls of fiber board disks clamped to shafts and provided with spiral grooves, to construct the knocker rolls each of one piece of metal with projecting teeth, to provide new means for adjusting the doctor blades relatively to the 20 ginning rolls, to provide air blast fans for directing the cotton against beater rolls, and to provide a passage with transverse panels with upwardly extending teeth over which 25 the cotton is carried for opening and straightening out the cotton fibers.

Additional objects of my invention will appear in the following complete specification, in which the present form of the invention 30 is disclosed.

In the drawings, similar characters of reference indicate corresponding parts in all the views, in which—

Figure 1 is a sectional elevation of my 35 cotton gin;

Fig. 2 is a side elevation of a cotton gin showing the driving mechanism;

Fig. 3 is a view of partial section, showing 40 one of the ginning rolls;

Fig. 4 is a plan view of one of the doctor blades, showing the means by which it is adjusted relative to the ginning roll;

Fig. 5 is an enlarged transverse sectional view, showing one of the ginning rolls and 45 a doctor blade in position relative thereto;

Fig. 6 is an enlarged view showing the means for opening and straightening out the cotton fibers;

Fig. 7 is a transverse sectional view of 50 Fig. 6;

Fig. 8 is a fragmentary view, showing in perspective one of the panels with its teeth opening and straightening the cotton fibers; and

Fig. 9 is a transverse sectional view of 55 one of the machine rolls.

By referring to the drawings, it will be seen that the casing 5 has dirt pockets 6, and that the pockets 6 are disposed opposite each other. Disposed in the frame 5 60 and journaled in the bearings 9 there are two feed rollers 7, with outwardly disposed teeth 8. These feed rollers rotate outwardly and downwardly, as shown by the arrows in Fig. 1 of the drawings, the teeth 8 of the 65 feed rollers 7 passing down adjacent the gauze 10, at the inner sides of the dirt pockets 6. It will therefore be seen that with the rotation of the feed rollers 7 the cotton will be moved down and against the 70 gauze members 10, so that dirt, leaves, etc., may pass through the gauze members into the dirt pockets 6. Above the feed rollers 7 there are feed rollers 11, 12, 13 and 14, these feed rollers 11, 12, 13 and 14 being 75 journaled in the frame, as shown in Figs. 1 and 2 of the drawings, for rotating as shown by the arrows in Fig. 1 of the drawings. Disposed in the frame below the feed rollers 7 there is a wedge-shaped member 80 15 for directing the cotton in the direction of the doctor blades 16. This wedge-shaped member 15 also covers the air conduit 17, which is provided for carrying air to the passage 18 between and under the ginning 85 rolls 19. The wedge-shaped member 15 has curved bottom members 20 which conform with and are disposed parallel with the peripheries of the ginning rolls 19, so that the ginning rolls 19 may rotate outwardly 90 and downwardly close to the said bottom members 20 and prevent the passage of cotton between the ginning rolls and the said bottom members.

As shown in Fig. 3 of the drawings, these 95 ginning rolls 19 are constructed with shafts 21 and 21^a, on which are mounted a plurality of fiber board disks 22, there being mounted on the shafts 21 and 21^a washers 23 which engage the said fiber board disks 22, the 100 washers 23 being held in position against the end fiber board disk 22 by the nuts 24 which mesh with threads on the shafts 21 and 21^a. These ginning rolls are constructed in this manner of fiber board disks at very little 105 expense. These fiber board disks are keyed to and are rigidly mounted on the shaft 21 in the manner described, which permits of

the displacement of the fiber board disks without any trouble if for any reason it be desired to renew them.

The ginning rolls 19 have spiral grooves 25, so that the cotton will be engaged by the ginning rolls at these spiral grooves, and will be carried past the doctor blades 16 and knocker rolls 26. These knocker rolls 26 are mounted on the shafts 27, which are journaled in the frame 5, as shown in Figs. 1 and 2 of the drawings. These knocker rolls are each constructed in one piece with projecting teeth. The knocker rolls 26 rotate inwardly and downwardly, while the ginning rolls rotate outwardly and downwardly. Disposed between these knocker rolls 26 and the ginning rolls 19 are the doctor blades 16, these doctor blades 16 having slots 28 in which are disposed the posts 29 which engage the members 30 and hold them in position against the doctor blades, the bolts 29 meshing in threaded orifices in the frame 5. The doctor blades 16 and the members 30 are disposed in the guide-ways 31, and between the rear ends 32 of the doctor blades and the shoulder 33 of the guide-way 31, there are disposed two wedge members 34 which taper in opposite directions as shown in Fig. 4 of the drawings. Meshing in threaded orifices in the frame 5, there are screws 35, one at each side, the screws being disposed for engaging the butts 36 of the wedge members 34 for moving them relatively to each other and to the frame 5 for adjusting the position of the doctor blades 16. It should be noted that the doctor blades 16 are inclined upwardly and inwardly, and engage the upper portions of the ginning rolls 19, the ginning rolls rotating in the direction of the doctor blades. The knocker rolls 26 are disposed in recesses 37 of the frame. In the bottoms of these recesses, there are slots 38 which permit foreign matters to be carried therethrough by the knocker rolls 26. Below the ginning rolls 19 there are disposed air blast fans 39, having paddles 40 which engage the air which enters through the conduit 17 and through the space 18 between the ginning rolls, these air blast fans carrying the air under the ginning rolls and in the direction opposite to that in which the ginning rolls travel. The air propelled by the fans 39 engages the cotton which is brought downward and inward by the ginning rolls 19, and forces this air outward and downward against the idler beater rolls 41 which are journaled in the frame 5. These idler beater rolls 41 are provided with teeth 42, as shown in the drawings.

As it will be seen by referring to Fig. 1 of the drawings, while the air blast fans 39 are rotated outward and downward by the movement of their shafts 43, the idler beater rolls 41 rotate inward and downward.

Disposed between the air blast fans 39 there are conduit members 44 which, with the ginning rolls 19, form passages 45 for the air from the conduit 17. As the cotton is moved downward from the air blast fans 39 it travels in the conduits 46 to the means shown in Figs. 6, 7 and 8 for opening and straightening out the cotton fibers. This means consists of a conduit 47 having transversely disposed panels 48 extending upward from the bottom 49 of the conduit and spaced from the top 50. Secured to and extending rearwardly from these panels 48 there are teeth 51. When the cotton is forced through this conduit in the direction of the arrow shown in Fig. 7 of the drawings, the teeth 51 will serve to open and straighten the cotton fibers. It will also be understood that there will be very little movement of air in the spaces 52 of the rear of the panels 48, and that, consequently, dirt may collect in these spaces 52 which may be removed from time to time.

As shown in Fig. 2, the bearings 9 are disposed in guideways 60 in the frame 5, the bearings 9 being held in adjusted position 90 by the screws 61. The feed wheels 7 are mounted on the shafts 62 journaled in the bearings 9, and on these shafts 62 are mounted the gear wheels 63 which mesh with each other. On one of the shafts 62 is mounted a gear wheel 64 with which meshes the gear wheel 65 on the shaft 66. Mounted on a cam 67 secured to the shaft 66 there is a link 68 which has a tooth 69 engaging the ratchet wheel 70 mounted on the shaft 12^a on which the feed roller 12 is mounted. This shaft 12^a is connected with the shaft 13^a by the gear wheel 71. A pulley 72 is mounted on the shaft 66, and this pulley 72 is connected with the pulley 73 by the belt 74. The pulley 73 is mounted on the shaft 21^a which is journaled in a bearing member 75 disposed in a guide-way 76 in the frame. The bearing member 75 is held in place by the screws 77 mounted on this shaft 21^a. There is also a friction wheel 78 which drives a friction wheel 79 secured to the shaft 27, there being also a friction wheel 80 which is secured to this shaft 27 and which drives the friction wheel 81 secured to the shaft 43 to which the beater roll 41 is also secured. The friction wheel 78 also drives the friction wheel 83 secured to the shaft 21, the friction wheel 83 driving the friction wheel 84 secured to the other shaft 27, and the friction wheel 85 secured to the shaft, said other shaft 27 driving the friction wheel 86 secured to the other shaft 43.

Having thus described my invention, I claim as new and desire to secure by Letters Patent:

1. In a cotton gin, two ginning rolls spaced apart, dividing members forming a conduit leading to the space between the ginning rolls, conduit members spaced from

the dividing members and coöperating with the ginning rolls to direct air from between the ginning rolls under the ginning rolls, fans disposed adjacent the conduit members 5 and disposed under the ginning rolls, and beater rolls at the outer sides of the fans.

2. In a cotton gin, two ginning rolls spaced apart, dividing members forming a conduit leading to the space between the ginning rolls, conduit members spaced from the dividing members and coöperating with the ginning rolls to direct air from between the ginning rolls under the ginning rolls.

3. In a cotton gin, a casing having a side 15 with a projection in which there is a recess, there being an opening at the bottom of the recess, a knocker roll rotatably mounted at the recess, a doctor blade projecting obliquely from without the casing to a position 20 at the inner side of the casing adjacent the knocker roll, means below the projection at the outer side of the casing for adjusting the position of the doctor blade, and a ginning roll disposed at the inner side of the 25 doctor blade and the knocker roll.

4. In a cotton gin, a ginning roll, a knocker roll disposed adjacent to the ginning roll, a doctor blade disposed for co-operating with the ginning and the knocker 30 rolls, a beater roll disposed below the doc-

tor blade, and a fan for directing an air blast at the side of the beater roll.

5. In a cotton gin, a ginning roll, a knocker roll having its axis at one side of the vertical plane of the axis of the ginning 35 roll, a doctor blade for coöperating with the ginning and knocker rolls, a beater roll disposed below the horizontal plane of the axis of the ginning roll, and a fan for directing air from the other side of the vertical 40 plane of the axis of the ginning roll down at the side of the beater roll.

6. In a cotton gin, a frame having dividing members therein forming a conduit, ginning rolls spaced apart with exposed surfaces at the outer sides of the 45 dividing members, means for coöperating with the ginning rolls for treating the cotton passing through the cotton gin, beater rolls disposed below the horizontal planes 50 of the ginning rolls, and fans for directing air down at the sides of the beater rolls.

In testimony whereof I have signed my name to this specification in the presence of two subscribing witnesses.

WILLIAM T. DODD.
